NORRIS ELMORE CLARK, DECEASED, LATE OF PLAINVILLE, CONNECTICUT, BY LIDA F. C. CLARK, EXECUTRIX, ASSIGNOR TO ROBERT S. ALLYN, TRUSTEE, OF NEW YORK, N. Y.

EXPANDED-METAL MACHINE.

1,361,138.

Specification of Letters Patent.

Patented Dec. 7, 1920.

Application filed September 12, 1919. Serial No. 323,297.

To all whom it may concern:

Be it known that NORRIS ELMORE CLARK, formerly a citizen of the United States of America, and residing at Plainville, Connecticut, but now deceased, did invent new and useful Improvements in Expanded-Metal Machines, of which the following is a specification.

This invention relates particularly to improvements in a machine of the type of Patent #1,224,877 of May 1st, 1917.

The main object is to enable the machine to operate more smoothly and produce a more uniform product under varying conditions of use to which the machine is subjected. Another object is to enable adjustments to be made to vary the action of the expansion.

It has been found in operation that the slitting of the metal in preparation for the expansion introduces local tension and tendency to distortion which sometimes causes irregularities in the product and trouble in the operation of the expander. To offset these difficulties I propose to drive the expanding rings or disks so as to provide tension on the alternate interior strips or interribs as the expansion takes place. In addition to this action I propose to transversely crimp the interribs as they enter the machine and before the fabric is expanded so as to counteract any buckling tendency which may have been started by the slitting action. In addition to these features I make the expanding rings larger in diameter than the disks which feed the marginal and corresponding interior unslotted strips so that the interribs are caused to pass around curves of larger radii. In addition to this feature I so locate the expanding rings that the full expansion is produced along a line somewhat in advance of the plane through the axes of the adjacent disks which feed the marginal and other interior unslotted strips so that there is a chance for the expanding mesh-work to adjust itself, so to speak.

Figure 1, is a side view of the parts of the machine particularly embodying my invention showing one of the housings and in dotted lines indicating the pitch lines of the

gears and sprockets for driving the feed disks and the expansion disks or rings.

Fig. 2, is a side view showing the feed disks and expansion rings.

Fig. 3, is a fragmentary view of the feed and expansion disks and the driving gears and sprockets.

Fig. 4, is an enlarged fragmentary detail showing the teeth for crimping the interribs.

The housing in the form shown is in two parts, the main part 6 and the cap 7.

A series of spaced feed disks such as 8 and 9, which may be termed "main disks," are secured on shaft 10 and coöperate with feed disks 11 and 12 on the shaft 13 and also with other disks 14 and 15 on shaft 16. These disks are all adapted and arranged to engage the marginal and interior unslotted strips of the partially slotted sheet. The marginal disks such as 8, 11 and 14 are preferably provided with tongues and grooves to engage small beads in the marginal strips so as to more securely hold the marginal strips and prevent them from running off the disks. Shaft 10 is provided with a gear 17 which meshes with gears 18 and 19 on shafts 13 and 16 respectively so that all three shafts rotate together, power being applied in any suitable manner preferably to shaft 10.

Shafts 10 and 16 are preferably supported by boxes such as 20 and 21, which are vertically adjustable in the housing by means of the bolts 22 and 23, the boxes being guided by plates such as 24 suitably secured to the housing. The shaft 13 is similarly mounted in boxes 25 but horizontally adjustable by means of bolts 26.

The expanding disks or rings 27-27 are mounted so as to rotate on bearing plates or disks 28 which are supported by brackets 29 and 30. The brackets 29 are carried by shaft 31 and the brackets 30 are carried by shaft 32. The shaft 31 is supported in boxes 33 which are horizontally adjustable by bolts 34 and 35 and vertically adjustable by bolts 36 and 37. The shaft 32 is carried by brackets 38 which are secured to the housings by bolts 39 which enable the brackets to be clamped direct to the housings or to be ad-

80

85

90

100

justed horizontally by inserting packing plates or shims between the brackets and the housings. These brackets are vertically adjustable by bolts such as 40—41. This 5 method of supporting the expanding disks or rings makes it possible to increase or decrease the expansion by lowering or raising the expanding disk relative to the feed disk. By horizontally adjusting the expanding 10 disk the point of maximum expansion which is directly below the center of the expanding disk may be moved closer to or farther away from the vertical plane containing the shafts of the upper and lower feed disks and the 15 line of contact where the marginal and interior unslotted strips are held.

Feed disks 42—42 coaxing with the expanding disks 27—27 are carried by a shaft 43 which has bearing boxes 44 horizontally 20 adjustable by bolts 45. These boxes are guided by plates such as 46 and 47, the latter of which also guides the bearing box 25 of the shaft 13. These disks 42 are driven from the shaft 16 by means of the 25 sprocket 48, chain 49 and sprocket 50 so as to give attractive force to the interribs by gripping the interribs between the disks 42 and 27 and by the friction of the expanding disks which are thus driven from the disks 42. By providing the disks 27 30 and 42 with teeth such as 51 and 52 (see Fig. 4) it is possible to crimp the interribs or corrugate them transversely as at 53 so as to foreshorten the interribs somewhat 35 before the expansion takes place and eliminate any tendency to buckle the interribs or distort the fabric.

Claims:—

1. In an expanding machine, sets of upper and lower feed disks arranged in pairs spaced apart from each other and other feed disks coaxing with one set of the first mentioned sets of pairs for feeding marginal and interior unslotted strips of a partially slotted sheet, the marginal feed disks being provided with tongue and grooved portions, rotating expanding members between adjacent disks of one of the first mentioned sets of disks and provided with 45 transverse teeth and toothed disks coaxing with the expanding members for crimping the interribs of the sheet.

2. In an expanding machine, sets of upper and lower feed disks arranged in pairs spaced apart from each other and other feed disks coaxing with one set of the first mentioned sets of pairs for feeding marginal and interior unslotted strips of a partially slotted sheet, the marginal feed disks 50 being provided with tongue and grooved portions, rotating expanding members between adjacent disks of one of the first mentioned sets of disks and provided with transverse teeth and toothed disks coaxing 55 with the expanding members for crimping 60 the interribs of the sheet, the axis of said expanding members being beyond the plane of the axes of the first two mentioned sets of disks whereby the complete expansion is allowed to take place on lines inclined forwardly in the direction of feed. 70

the interribs of the sheet, the axis of said expanding members being beyond the plane of the axes of the first two mentioned sets of disks whereby the complete expansion is allowed to take place on lines inclined forwardly in the direction of feed. 70

3. In an expanding machine, sets of upper and lower feed disks arranged in pairs spaced apart from each other and other feed disks coaxing with one set of the first mentioned sets of pairs for feeding marginal and interior unslotted strips of a partially slotted sheet, the marginal feed disks being provided with tongue and grooved portions, rotating expanding members between adjacent disks of one of the first mentioned sets of disks and provided with transverse teeth and toothed disks coaxing 75 with the expanding members for crimping the interribs of the sheet, the axis of said expanding members being beyond the plane of the axes of the first two mentioned sets of disks whereby the complete expansion is allowed to take place on lines inclined 80 forwardly in the direction of feed, the radius of the expanding members being greater than the radius of the disks of the set whose axis is nearest to the axis of the expanding members. 85

4. In an expanding machine, sets of upper and lower feed disks arranged in pairs spaced apart from each other and other feed disks coaxing with one set of the first mentioned sets of pairs for feeding marginal and interior unslotted strips of a partially slotted sheet, the marginal feed disks being provided with tongue and grooved portions, rotating expanding members between adjacent disks of one of the first mentioned sets of disks and provided with transverse teeth and toothed disks coaxing 90 with the expanding members for crimping the interribs of the sheet, the radius of the expanding members being greater than the radius of the disks of the set whose axis is nearest to the axis of the expanding members. 95

5. In an expanding machine, a series of feed disks spaced apart on a common axis, two series of feed disks coaxing with said first mentioned disks for successively engaging unslotted strips as they pass partially around the disks of the first series, a series of rotary expanding members between the disks of the first mentioned series 100 of disks and the disks of the third series of disks and feed disks coaxing with said rotary expanding members between the disks of the second and third series of disks. 110

6. In an expanding machine, a series of feed disks spaced apart on a common axis, two series of feed disks coaxing with said first mentioned disks for successively engaging unslotted strips as they pass partially around the disks of the first series, a 125 130

- series of rotary expanding members between the disks of the first mentioned series of disks and the disks of the third series of disks and feed disks coacting with said rotary expanding members between the disks of the second and third series of disks, the radius of the rotary expanding members being greater than the radius of the disks of the first mentioned series of feed disks.
7. In an expanding machine, a series of feed disks spaced apart on a common axis, two series of feed disks coacting with said first mentioned disks for successively engaging unslotted strips as they pass partially around the disks of the first series, a series of rotary expanding members between the disks of the first mentioned series of disks and the disks of the third series of disks and feed disks coacting with said rotary expanding members between the disks of the second and third series of disks, the axis of said rotary expanding members being beyond the plane of the axes of the disks of the first and third series of feed disks whereby the expansion takes place along lines inclined forwardly in the direction of feed.
8. In an expanding machine, a series of feed disks spaced apart on a common axis, two series of feed disks coacting with said first mentioned disks for successively engaging unslotted strips as they pass partially around the disks of the first series, a series of rotary expanding members between the disks of the first mentioned series of disks and the disks of the third series of disks and feed disks coacting with said rotary expanding members between the disks of the second and third series of disks, and means for vertically adjusting the disks of the first and third series of feed disks, means for horizontally adjusting the other feed disks, said rotary expanding members being horizontally and vertically adjustable.
9. In an expanding machine, a series of feed disks spaced apart on a common axis, two series of feed disks coacting with said first mentioned disks for successively engaging unslotted strips as they pass partially around the disks of the first series, a series of rotary expanding members between the disks of the first mentioned series of disks and the disks of the third series of disks, and feed disks coacting with said rotary expanding members between the disks of the second and third series of disks, the rotary expanding members and the coacting disks having teeth for crimping the interribs of the sheet while the expansion of the meshwork is taking place.
10. In an expanding machine, two coacting sets of spaced rotary feed disks on parallel axes, means for feeding unslotted strips of a partially slotted sheet around the curved guiding faces of the disks of one set of feed
- disks, a rotating expanding disk between adjacent pairs of feed disks, said expanding disk being of larger diameter than the disks around which the unslotted strips are guided and the axis being in a plane beyond the plane of the axes of the feed disks, and means for driving said expanding disk.
11. In an expanding machine, two coacting sets of spaced rotary feed disks on parallel axes, means for feeding unslotted strips of a partially slotted sheet around the curved guiding faces of the disks of one set of feed disks, a rotating expanding disk between adjacent pairs of feed disks, said expanding disk being of larger diameter than the disks around which the unslotted strips are guided and the axis being in a plane beyond the plane of the axes of the feed disks, means for driving said expanding disk, and means for transversely crimping the interrib of the sheet while the meshwork is being formed.
12. In an expanding machine, two coacting sets of spaced rotary feed disks on parallel axes, means for feeding unslotted strips of a partially slotted sheet around the curved guiding faces of the disks of one set of feed disks, a rotating expanding disk between adjacent pairs of feed disks, said expanding disk being of larger diameter than the disks around which the unslotted strips are guided and the axis being in a plane beyond the plane of the axes of the feed disks, means for driving said expanding disk, and means for adjusting the expanding disk vertically and horizontally.
13. In an expanding machine, two coacting sets of spaced rotary feed disks on parallel axes, means for feeding unslotted strips of a partially slotted sheet around the curved guiding faces of the disks of one set, a rotating expanding disk between adjacent pairs of feed disks and means for transversely crimping the interrib of the sheet while the meshwork is being formed.
14. In an expanding machine, two coacting sets of spaced rotary feed disks on parallel axes, means for feeding unslotted strips of a partially slotted sheet around the curved guiding faces of the disks of one set, a rotating expanding disk between adjacent pairs of feed disks, means for transversely crimping the interrib of the sheet while the meshwork is being formed, and means for adjusting the expanding disk vertically and horizontally.
15. In an expanding machine, means for guiding marginal and interior unslotted strips of a partially slotted sheet in a curved plane, rotary expanding members alternating with said guiding means and having radii greater than the radius of the curved guiding means, and means for transversely crimping the interribs of the sheet while the expansion of the meshwork is taking place.

16. In an expanding machine, upper and lower sets of spaced feed disks for unslotted strips, an expanding ring located between laterally adjacent feed disks, the center of 5 said ring being beyond the plane of the axes of said feed disks and means for driving said expanding ring.
17. In an expanding machine, upper and lower sets of spaced feed disks for unslotted strips, an expanding ring located between laterally adjacent feed disks, the center of 10 said ring being beyond the plane of the axes of said feed disks, said expanding ring being of greater radius than the feed disks whose axis is nearest to it.
18. In an expanding machine, upper and lower sets of spaced feed disks for unslotted strips of a partially slotted sheet, an expanding ring located between laterally 15 adjacent feed disks, the center of said ring being beyond the plane of the axes of said feed disks, said expanding ring being of greater radius than the feed disks whose axis is nearest to it, and means for crimping 20 the interrib of the sheet before it reaches the plane of said axes.
19. In an expanding machine, upper and lower sets of spaced feed disks for unslotted strips of a partially slotted sheet, an 25 expanding ring located between laterally adjacent feed disks, and means for crimping the interrib of the sheet before it reaches the plane of the axes of said feed disks.
20. In an expanding machine, upper and lower sets of spaced feed disks for unslotted strips of a partially slotted sheet, an expanding ring located between laterally adjacent feed disks, and means for crimping the interrib of the sheet while expansion is taking 30 place, said expanding ring being of greater radius than the feed disks.
21. In an expanding machine, upper and lower sets of spaced feed disks for unslotted strips of a partially slotted sheet, an expanding ring located between laterally adjacent feed disks, and means for crimping the interrib of the sheet before it reaches the plane of the axes of said feed disks, said expanding ring being adjustable vertically 35 and horizontally.
22. In an expanded metal machine, a set of vertically adjustable feed disks spaced apart on a common axis, a set of horizontally adjustable feed disks coacting therewith, a set of vertically adjustable feed disks coacting with said first set of disks and in line with the disks of the second set, and vertically and horizontally adjustable expanding members between the adjacent 40 series of feed disks.
23. In an expanded metal machine, a set of vertically adjustable feed disks spaced apart on a common axis, a set of horizontally adjustable feed disks coacting therewith, a set of vertically adjustable feed 45 disks coacting with said first set of disks and in line with the disks of the second set, and driving members adjustable with said expanding members.
24. In an expanded metal machine, a set of feed disks spaced apart on a common axis, a set of feed disks coacting therewith, means for horizontally adjusting said second set of feed disks, a set of feed disks coacting with said first set of disks and in line with the disks of the second set, means for vertically adjusting said third set of disks 50 and vertically and horizontally adjustable expanding members between the adjacent series of feed disks.
25. In an expanded metal machine, a set of feed disks spaced apart on a common axis, a set of feed disks coacting therewith, means for horizontally adjusting said second set of feed disks, a set of feed disks coacting with said first set of disks and in line with the disks of the second set, means for vertically adjusting said third set of disks 55 and expanding members between the adjacent series of feed disks.
26. In an expanded metal machine, a set of feed disks spaced apart on a common axis, a set of feed disks coacting therewith, a set of feed disks coacting with said first set of disks and in line with the disks of the second set, expanding members between the adjacent series of feed disks, means for horizontally adjusting said expanding members and horizontally adjustable driving members coacting with said expanding members.
27. In an expanded metal machine, a set of feed disks spaced apart on a common axis, a set of feed disks coacting therewith and adjustable to and from the same, a second set of feed disks coacting with said first set of disks and in line with the disks of the second set and adjustable to and from the first disks and adjustable expanding members between the adjacent series of feed disks.
28. In an expanded metal machine, a set of feed disks spaced apart on a common axis, a set of feed disks coacting therewith and adjustable to and from the same, a second set of feed disks coacting with said first set of disks and in line with the disks of the second set and adjustable to and from the first disks, adjustable expanding members between the adjacent series of feed disks 100 and driving members adjustable with said expanding members.
29. In an expanded metal machine, a set of feed disks spaced apart on a common axis, a set of horizontally adjustable feed 105 disks coacting with said first set of disks and in line with the disks of the second set, and driving members adjustable with said expanding members.

- disks coacting therewith, a set of vertically adjustable feed disks coacting with said first set of disks and in line with the disks of the second set, horizontally adjustable expanding members between the adjacent series of feed disks, and horizontally adjustable driving disks coacting with said expanding members.
30. In an expanded metal machine, a set of feed disks spaced apart on a common axis, a set of feed disks coacting therewith, means for adjusting said second set of feed disks toward the first set, a set of feed disks coacting with said first set of disks and in line with the disks of the second set, means for adjusting said third set of disks toward the first set, and expanding members adjustable in two directions between the adjacent series of feed disks.
31. In an expanded metal machine, a set of feed disks spaced apart on a common axis, a set of feed disks coacting therewith, a set of feed disks coacting with said first set of disks and in line with the disks of the second set, rotary expanding members between the adjacent series of feed disks and means for adjusting said expanding members in two directions independently at substantially right angles to each other.
32. In an expanded metal machine, a set of feed disks spaced apart on a common axis, a set of feed disks coacting therewith, a set of feed disks coacting with said first set of disks and in line with the disks of the second set, expanding members between the adjacent series of feed disks, means for adjusting said expanding members and adjustable driving members coacting with said expanding members.
33. In an expanded metal machine, a set of feed disks spaced apart on a common axis, a set of feed disks coacting therewith and adjustable to and from the same, a second set of feed disks coacting with said first set of disks and in line with the disks of the second set and adjustable to and from the first disks, adjustable expanding members between the adjacent series of feed disks and crimping means adjacent said expanding members.
34. In an expanded metal machine, a set of feed disks spaced apart on a common axis, a set of feed disks coacting therewith, means for adjusting said second set of feed disks toward the first set, a set of feed disks coacting with said first set of disks and in line with the disks of the second set, means for adjusting said third set of disks toward the first set, expanding members adjustable in two directions between the adjacent series of feed disks and crimping means adjacent said expanding members.
35. In an expanded metal machine, a set of feed disks spaced apart on a common axis, a set of feed disks coacting therewith, a set of feed disks coacting with said first set of disks and in line with the disks of the second set, expanding members between the adjacent series of feed disks, means for adjusting said expanding members and adjustable driving disks coacting with said expanding members.
36. In an expanded metal machine, a set of feed disks spaced apart on a common axis, a set of feed disks coacting therewith, a set of feed disks coacting with said first set of disks and in line with the disks of the second set, rotary expanding members between the adjacent series of feed disks, crimping members adjacent said expanding members and means for adjusting said expanding members in two directions independently at substantially right angles to each other.
37. In combination a series of spaced main disks, two feed disks coacting with each main disk, a rotary expanding member between each two adjacent main disks, crimping means adjacent each expanding member for crimping the interribs of a sheet while the slotted portions are being expanded.
38. In combination a series of spaced main disks, two feed disks coacting with each main disk, a rotary expanding member between each two adjacent main disks, crimping means adjacent each expanding member for crimping the interribs of a sheet while the slotted portions are being expanded, and means for adjusting said crimping means.
39. In combination a series of spaced main disks, two feed disks coacting with each main disk, a rotary expanding member between each two adjacent main disks, said expanding members being of larger radii than said main disks and arranged beyond the said disks so that the interribs of a partially slotted sheet are carried around curves of larger radii than the marginal strips of the sheet and the maximum expansion occurs beyond the feed disks.
40. In combination a series of spaced main disks, two feed disks coacting with each main disk, a rotary expanding member between each two adjacent main disks, each expanding member being of larger radius than said main disks and arranged beyond said main disks so that the interribs of a partially slotted sheet are carried around curves of larger radii than the marginal strips of the sheet, and so that the maximum expansion occurs beyond the feed disks and crimping means adjacent each expanding member for crimping the interrib while the slotted portions are being expanded.
41. In combination a series of spaced main disks, two feed disks coacting with each main disk, a rotary expanding member between each two adjacent main disks, each expanding member being of larger radius

than said main disks and arranged beyond said main disks so that the interribs of a partially slotted sheet are carried around curves of larger radii than the marginal 5 strips of the sheet, and so that the maximum expansion occurs beyond the feed disks and crimping means adjacent each expanding member for crimping the interrib while the

slotted portions are being expanded, and means for adjusting each expanding member up and down and forward and back with relation to said feed disks. 10
